Patented Oct. 26, 1976

242,051

WALL MOUNTED MATCH HOLDER

Linda C. Brown, Box 219, Clovis, N. Mex. 88101

Filed Mar. 30, 1976, Ser. No. 671,999

Term of patent 14 years

Int. Cl. D27—99

U.S. Cl. D27—32

Fig. 2

Fig. 1

Fig. 3

FIG. 1 is a perspective view of a wall mounted match holder showing my new design;

FIG. 2 is a front elevational view thereof; and

FIG. 3 is a top plan view thereof.

The broken line showing of the matches in FIG. 1 is for illustrative purposes only.

I claim:

The ornamental design for a wall mounted match holder, as shown and described.
